UNITED STATES PATENT OFFICE

HENRY COWLES AND JAMES K. NORRIS, OF UTICA, NEW YORK, ASSIGNEES, BY MESNE ASSIGNMENTS, TO NATIONAL RADIATOR CORPORATION, OF DOVER, DELAWARE, A CORPORATION OF DELAWARE

SECTIONAL FURNACE

Application filed January 11, 1923, Serial No. 612,004. Renewed January 18, 1929.

Our invention relates to a sectional furnace of known type which is made up of an assembled series of hollow, water-containing sections and in which it is sought to obtain

5 more perfect combustion reaction and to render the furnace smokeless by the introduction of auxiliary air, the structure and objects thus generally recited being familiar in this art. Our invention is concerned more particularly with the construction of the bridge wall and related parts in a furnace of the type described and with the furnace structure with which they cooperate, and, for promoting combustion in and beyond the firebox, 10 utilizes air heated in the ashpit before its passage through the water-containing bridge wall as well as during such passage to the firebox.

Referring to the drawings:

20 Fig. 1 is a side elevation of a furnace embodying our invention, parts of the side walls of the sections being broken away to show interior construction in section on the line I—I Fig. 2.

25 Fig. 2 is a front elevation of the throat section and ashpit beneath the same, part of the front wall adjacent the throat being broken away to show internal structure in section.

Fig. 3 is a horizontal section on the line 30 III—III of Fig. 2.

Fig. 4 is a longitudinal section of a modification, and

35 Fig. 5 is a horizontal transverse section illustrating the construction of the air delivery means employed in this modification.

The furnace is made up of cast hollow water-containing sections 1 bolted together in the ordinary way and supported by base members 2 at the sides of the furnace connected by 40 transverse front and rear plates 3 and 4 respectively, the front plate being provided with the usual door and damper arrangements not requiring description. A transverse divisional plate 5 forms the rear wall

45 of the ashpit. The assembled sections form the firebox 6, provided with the grate 7, intermediate combustion and rear flue space 8, upper return side flues 9 at each side of the furnace and the central escape flue 10 leading to the smoke pipe, the flow of the fire gases be-

ing indicated by the arrows. The front unit 1^a is provided with the fuel feed door 11 and clean-out doors 12 above the same, whereby all the flues are rendered accessible.

Referring to the form of the invention illustrated in Figs. 1 to 3, inclusive, the throat section, which is designated as 1^b, provides in a single casting, a water-containing bridge wall 13 and a depending water-containing baffle, or firebox end wall 14. These walls, 55 the water-containing bridge wall and the water-containing baffle or curtain wall, form between them a transversely elongated throat for the passage of the fire gases. Air flues 15 leading from the ash pit to the throat space and water-protected on all sides, are arranged in a transverse series across the furnace and are here shown in their preferred form and location, as a series of tubes cast in the section 1^b and extending upwardly from the rear part of the ash pit through the body of water contained in the bridge wall 13. They thus receive air previously heated by radiation in the ash pit and distribute it 60 throughout the width of the fire gas flow and to all parts thereof and deliver it crosswise of said flow. The upper side of the throat formed by the lower edge of the wall 14 may be provided as shown, with air delivery means of substantially the character set forth 65 in the patent to Doherty No. 1,402,843, granted January 10, 1922, and in which a forwardly projecting water-containing ledge 16, at the bottom of the wall 14, forms with adjacent parts of the wall and the transverse member 17, an air delivery passage 18 from which air escapes to the throat through openings 19 in the ledge 16. Air enters 70 through the inlet bushings 20 at each side of the furnace, the inflow being controlled by dampers 20'. The employment of this additional auxiliary air delivery means is advantageous but not essential to the present invention.

In the modification shown in Figs. 4-5, 95 the vertical air flues 15^a are water-protected on their front and sides only where the heat would otherwise be very intense but are unprotected on the rear side save by the transverse cover plate 21 closing the otherwise 100

open rear side of said flues. This plate, being out of the way of stoking tools, may be a slab of refractory material. In this construction, as in the preferred form, air heated in the ash pit is conducted therefrom through the water-containing bridge wall and delivered throughout the entire width of the throat to the fire gas flow and crosswise the same. The bridge wall 13 may have a vertical front side or be provided with a curved recess to accommodate the oscillation of the nearest grate bar.

It will be apparent that the invention inheres both in the combination described and in the construction of the section or sections containing the auxiliary air flues.

We claim:

1. A sectional furnace made up of an assembled series of cast hollow water-containing transverse sections having a grate and ash pit thereunder and forming by water-cooled metal walls a firebox, water-cooled flue space in communication therewith, one of said sections forming both a hollow water-containing metal baffle wall depending below the roof of the fire-box, extending across the furnace and exposed to the fire gases, and a hollow metal water-containing bridge wall beneath said depending baffle wall and spaced therefrom, said bridge wall being provided with a transverse series of spaced vertical air flues having their front sides water-protected leading heated air from said ash pit and delivering it upward crosswise of the current of fire gases passing between the bridge wall and baffle wall.

2. In a sectional furnace, a cast hollow water-containing transverse section, having a depending water-containing curtain wall and an upstanding water-containing bridge wall opposed thereto both formed as a part of that one section and forming between them a transversely elongated throat, both of said walls having formed therein water-cooled passages for admitting air to the throat.

In testimony whereof, we have signed this specification.

HENRY COWLES.
JAMES K. NORRIS.
